C. CHAPLIN

WINDOW DOG KENNEL

Filed Feb. 4, 1922

Fig. 1.

UNITED STATES PATENT OFFICE.

CLAIRES CHAPLIN, OF NEW YORK, N. Y.

WINDOW DOG KENNEL.

Application filed February 4, 1922. Serial No. 534,121.

To all whom it may concern:

Be it known that I, CLAIRE CHAPLIN, a citizen of Great Britain, and a resident of the city of New York, borough of Manhattan, in the county and State of New York, have invented a new and Improved Window Dog Kennel, of which the following is a full, clear, and exact description.

This invention relates to dog kennels and particularly to an improved kennel which may be used as an attachment to a house whereby a dog may be allowed to live in the house ordinarily.

The object of the invention is to provide a kennel which may be readily mounted on a window or other support in apartment houses or other buildings and arranged so that access may be secured thereto at any time from a point interiorly of a building.

Another object of the invention is to provide a dog kennel adapted to be mounted on the outer window sill and connected to the window frame in such a manner as to be properly supported, the arrangement being such that the drain board thereof will engage the window pane so as to prevent all or most of the water or rain from entering the kennel.

In the accompanying drawing—

Figure 1 is a fragmentary vertical sectional view through a window and part of a wall with an embodiment of the invention shown applied thereto, said embodiment being partially in section.

Figure 2 is a top plan view of the kennel shown in Figure 1, certain parts being broken away.

Figure 3 is an elevation of the kennel shown in Figure 2, the upper parts of the supporting arms being broken away.

Referring to the accompanying drawing by numerals, 1 indicates a wall provided with a window sill 2 and a window frame 3 which carries a sash 4. The construction just described is an ordinary construction found in buildings in common use. In apartment houses and also in some other houses it is difficult to provide proper quarters for a pet dog so as to give him plenty of fresh air and at the same time provide for his comfort.

In order to take care of a dog in an apartment and to provide means for overcoming

the above mentioned difficulties, a kennel is constructed as shown in the accompanying drawing which is mounted on the outer part of the sill 2. This kennel is provided with a bottom 5 having an upwardly extending flange 5' to make the bottom water tight. This bottom may be wood or any other desired material and to it a number of spaced uprights 6 are secured, said uprights being connected to upper strips 7 and 7' whereby a form of cage is provided, said cage having a front plate 8 through which supporting screws 9 extend, said screws projecting into the window frame 3. A lid 10 is removably mounted on the strips 7 though normally held thereto by thumb screws 11 passing through the cover and also through a threaded member 12 integral with or rigidly secured to the strip 7. The cover 10 is provided with a drain board 13 hinged to the cover by suitable hinges 14. This drain board is designed to rest against the pane of glass 15 so as to prevent water from entering the kennel. In order to hold this drain board in proper shape and prevent any movement caused by wind or other force, a set screw 16 is fitted into each of the brackets 17 and bears against part of the frame 3. In order to brace and also additionally support the bottom 5 and associated parts, a cross bar 18 is connected to bottom 5 and is bent at 19 and 20 so that it may extend upwardly and form the bracing bars 21 and 22 which bracing bars are connected to the frame 3 by suitable screws 23. These screws may be in the nature of thumb screws or any other desired form provided they act to properly connect the members 21 and 22 to the frame.

The members 21 and 22 are shown in Figure 3 as integral with the plate or bar 18 but it will be understood that they may be made separate and secured thereto in any desired manner. It will be noted that by providing spaced uprights 6, an ample volume of air may be continually provided for a dog positioned in the kennel while anyone may secure access to the interior of the kennel by merely raising the sash 4. This arrangement also permits the owner to examine the dog from time to time by merely looking through the window pane. It is intended that the kennel shall be mounted preferably

at some inconspicuous place and outside of the window pane so as to be in effect completely out of a room.

What I claim is:—

- 5 1. A window kennel comprising a box structure having a flanged bottom to render the same water-tight, strips secured to said bottom extending upwardly to form a foraminous wall for the box, a removable lid 10 therefor, means to secure said lid in place adjacent the side walls of the box, a drain member at one end of said lid extending at an angle thereto and means at the ends of said drain member to clamp the same to the 15 frame of a window.
2. A window kennel comprising a bottom provided with upwardly extending flanges all around, a solid top, a foraminous vertical wall structure between the bottom 20 and the top secured to said flange and means extending across the bottom approximately on the medial line thereof, said means hav-

ing arms at the ends thereof extending upwardly and rearwardly and adapted to removably be secured at their upper ends to a 25 window frame.

3. A window kennel comprising a foraminous box structure having a solid bottom flanged upwardly to retain in the bottom water and the like, a drain board for said box structure hinged to the top thereof at the rear and adapted to bridge the space between the box and a window pane when the box is secured to the window, an ear at each 30 end of said drain board provided with a threaded opening and a screw passing through said threaded opening for locking said board in place on the window frame permitting the sash carrying the window pane against which said drain board bears 35 to be opened and closed without changing the position of the drain board.

CLAI'RE CHAPLIN.
